E. A. BURROWS

REFRIGERATING APPARATUS

Filed April 4, 1924

UNITED STATES PATENT OFFICE.

EASTMAN A. BURROWS, OF CHICAGO, ILLINOIS, ASSIGNOR TO LLOYD G. COPEMAN AND EDWIN W. ATWOOD, BOTH OF FLINT, MICHIGAN.

REFRIGERATING APPARATUS.

Application filed April 4, 1924. Serial No. 704,098.

This invention relates to refrigerator apparatus and has for its object a refrigerator apparatus intended primarily for use in apartment buildings. It is the object of the invention to have a storage tank in the basement or elsewhere containing a cooling medium such as ice water. This is pumped at measured time intervals through the refrigerator boxes in the various apartments. The time interval between the pumping operations is adjustable in a very simple manner by means of a bleeding operation from one chamber of the storage tank to the other. By a suitable valve the rate of bleed may be altered to alter the time interval between pumping operations.

This bleeding operation which is regulatable by simply turning a valve, forms a simple equivalent for clock mechanism to determine the times at which the pumping operations can be carried on. The bleeding operation acts very much in the same way that an ordinary hour glass does in measuring intervals of time. So far as I am aware, a cooling medium has heretofore never been distributed to various points of use by means of a force pump controlled at measured intervals, especially when controlled by a bleeding operation of a liquid.

In the drawings:

Fig. 1 is a side elevation of the apparatus, partly in section somewhat diagrammatic in nature.

Fig. 2 is an enlarged vertical section through the tanks and valve for controlling the flow.

a designates the water pump driven by an electric motor *b*, which in turn is controlled by a switch *c* automatically actuated in a manner later to be described. The water line *d* leads from the pump through the refrigerator box *e* and thence through the line *f*, where it discharges into the larger ice tank *g*.

The large ice tank is divided or partitioned off at one end to form an ice and ice water chamber *h* and a smaller water chamber *i*. These two chambers are connected by the pipes *j* in which a bleeder valve *k* is

located so that the ice water may be siphoned from the large chamber to the small chamber. The bleeder valve controls the rate of flow of the ice water during the siphoning action.

Referring to Fig. 2, it will be seen that as the bleeder valve is turned down the valve opening may be decreased in size, thereby decreasing the flow of water from the large chamber to the small chamber.

A float *m* is located in the smaller chamber, and as the water is siphoned from the large to the smaller chamber, the water level in the small chamber will rise and carry with it the float *m*. A rod *n* is secured to the float and extends upwardly through the cover of the tank. The upper end of the rod is threaded (as shown in Fig. 2) so that the nuts *o* and *p* may be adjustably secured near the upper end of this rod. A switch arm *q* is provided with a hole *r* through which the rod *n* is adapted to be threaded.

Referring to Fig. 1, I have indicated by a dot and dash line the water line in the large ice and ice water chamber as *A*; the water level in the small tank before the water is siphoned into it is designated *B*. As the water is siphoned from the large tank to the smaller tank, the water level in the small tank will rise to a point designated *C* in Fig. 1. During this time the rod *n* will be pushed upwardly and the nut or collar *o* will strike the switch arm *q* and raise the same to the dotted line position as shown in Fig. 1. This will actuate the switch to close the current through the motor, thereby starting the pump in operation.

A pipe *s* connects the bottom of the small chamber *i* to the pump so that as the pump is operated it will pump the water from the small tank into the pipe *d*, thence through the refrigerator box, then through the pipe *f* into the large ice water chamber *h*. The amount of water that is allowed to flow through the bleeder valve is regulated so that the pump will discharge the water from the small chamber *i* faster than it flows in. In this way the water level in the small chamber is lowered and consequently

the float and rod n is also lowered. The nut or collar p carried by the rod n is adapted to engage the switch arm to move the same downwardly, thereby opening the switch 5 and stopping the motor and pump when the water in the small chamber reaches a predetermined level. The cycle of operation is now repeated, the water in the large ice chamber being allowed to siphon into the 10 smaller chamber until the switch is again operated by the raising of the water level in the small tank, as has been described.

By adjusting the opening in the bleeder valve, the rate of flow of the water between 15 the two chambers may be increased or decreased depending upon the time interval desired. If it is desired to run the cold water through the refrigerator box for a longer period of time, the bleeder valve opening is 20 increased to allow the water to siphon from one tank to the other faster, thereby causing the level of the water in the small tank to lower at a slower rate. This will also increase the rate at which the water level rises 25 in the smaller tank, thereby decreasing the time interval between the flushing of the refrigerator box.

Obviously, a decrease in the amount of 30 water pumped through the box can be obtained by decreasing the bleeder valve opening, thereby allowing the water level in the smaller tank to fall more rapidly. This will result in the pumping of a smaller quantity of water through the box since the 35 pump is operated at longer intervals than it was when the bleeder valve was wide open. It is also evident that when the bleeder valve opening is decreased in size thereby decreasing the flow of water therethrough, the small chamber will fill up at a slower 40 rate than when the bleeder valve is wide open. Thus, the time between the flushings of the box is of longer duration.

In this matter any desired adjustment of 45 the water flow can be obtained. A further adjustment is possible by the means of the nuts or collar o and p which are adjustably secured to the end of the rod n . An adjustment of these nuts or collars further apart, 50 will flush the box for a longer duration of time and increase the time interval between the flushings, while the shortening of the distance between these two collars will cause the box to be flushed at shorter intervals of time and for shorter periods of time.

Ice, designated t , may be placed in the 55 chamber h for cooling the liquid contained therein and for maintaining the said liquor at a low temperature. During the winter, the water from the city mains is sufficiently 60 cold so as not to require any additional means. I have so connected my refrigerating apparatus to the water main that by turning the valve u off, the water that is used in the household will be caused to first

flow through the refrigerator box for the purpose of cooling the same. To do this, I open valves v and v' and close valves w and W' , thereby causing the water from the water main to flow through the pipe line, x 70 thence through the pipe line v , line d , thence through the box c and return through the line f and line z before passing to the service line 1.

What I claim is:

1. In a refrigerating apparatus, the combination of a refrigerator box, a two-chamber storage tank containing a cooling medium, a conduit leading from one chamber of the storage tank passing through the refrigerator box and returning to the other chamber of the storage tank, means for forcing water through said conduit, means for bleeding water at a slower rate of flow than the capacity of said conduit from one chamber 85 to the other chamber in said storage tank, and means controlled by said bleeding action for governing the operation of the means which forces the water through the conduit. 90

2. In a refrigerator apparatus, the combination of a refrigerator box, a two-chamber storage tank containing a cooling medium, a conduit leading from one chamber of the storage tank passing through the refrigerator box and returning to the other chamber of the storage tank, means for forcing water through said conduit, adjustable means for bleeding water at different rates 95 of flow but less than the capacity of the conduit from one chamber to the other chamber in said storage tank, and means controlled by said bleeding action for governing the operation of the means which forces the water through the conduit. 100

3. In a refrigerating apparatus, the combination of a refrigerating box, an ice tank partitioned so as to form two chambers for holding a cooling liquid, one of which has a larger capacity than the other, means connecting the two chambers whereby the liquid may flow from the larger to the smaller chamber to raise the level of the liquid therein, a pipe line connected to the smaller chamber leading through the box and discharging into the large chamber, a pump for promoting circulation through said pipe line which has a capacity greater than that of the connecting means between the two chambers, a motor for driving said pump, a 110 switch for controlling the motor, and means contained within the small chamber engaging with the switch, whereby the motor will shut off when the water level in the small chamber reaches a predetermined low level, and which will allow the level of the liquid in the smaller chamber to again rise. 115

4. In a refrigerating apparatus, the combination of a refrigerating box, an ice tank partitioned off so as to form two chambers 120

130

for holding a cooling liquid, means for siphoning said cooling liquid from one chamber to the other, a pipe line having a greater capacity than the means for siphoning the liquid from one chamber to the other, and which is connected to one chamber leads through the box and discharges into the other chamber, a pump and motor for promoting circulation through said pipe line and withdrawing the liquid from the first mentioned chamber faster than the liquid enters therein, a switch for controlling said pump and motor, a float located in the chamber from which the liquid is taken to force the same through the box, and means for connecting said float to the switch mechanism whereby the switch is actuated upon the lowering of the water level of said chamber to shut off the pump to allow the liquid to again rise in the float chamber.

5. In a refrigerating apparatus, the combination of a refrigerating box, an ice tank partitioned so as to form one large chamber and a smaller chamber, said chambers adapted to hold a cooling liquid, means for bleeding said liquid from the large chamber to the smaller chamber at a relatively slow speed, a pipe line connecting with the smaller chamber leading through the box and discharging into the large chamber, a pump and motor for promoting circulation through said pipe line having a greater capacity than the means for bleeding the liquid from one chamber to the other, a switch for controlling said motor and pump, a float located in the smaller chamber, a rod connected thereto, and adjustable means carried by said rod adapted to engage the switching mechanism for actuating the switch off or on as the water level in the small chamber lowers or rises.

6. In a refrigerating apparatus, the combination of a refrigerating box, an ice tank adapted to hold a cooling liquid, said tank divided into two chambers one of which is smaller than the other, siphoning means connecting the two chambers whereby the liquid in the large chamber may be siphoned into the smaller chamber, a bleeder valve connected with said siphoning means for controlling the flow of water therethrough, a pipe line connected to the said smaller chamber leading through the box and discharging into the large chamber, a pump for forcing the cooling liquid from the smaller chamber into the pipe line, means for actuating said pump, and means for shutting off the pump when the liquid level in the small tank reaches a predetermined point.

7. In a refrigerating apparatus, the combination of a refrigerating box, a tank for holding a cooling liquid, said tank divided into two chambers, a pipe line leading from one chamber through the box and discharging into the other chamber, means for bleed-

ing the liquid from the one chamber to the other chamber and including a bleeder valve for adjusting the flow therefor, a pump for pumping the liquid from the one chamber to the pipe line, means for operating the said pump, a float contained within said chamber adapted to rise and fall as the level of the liquid in the said chamber rises and falls, a rod connected to said float, collars adjustably secured on the end of said rod and spaced apart, and a switch mechanism for controlling the operation of said pump operating means including a switch arm provided with a hole, said rod adapted to be threaded through said hole, the said collars positioned on either side of said switch arm and adapted to engage said switch arm, whereby the switch arm is actuated as the liquid level of the smaller tank rises or falls.

8. In a refrigerating apparatus, the combination of a refrigerating box, a storage tank partitioned off so as to form two chambers for holding a cooling liquid, means for bleeding the cooling liquid from one chamber to the other at a relatively slow speed, a pipe line connecting one chamber, leading through the box and discharging into the other chamber and having a greater capacity than the means for bleeding the liquid from one chamber to the other, a pump and motor for promoting circulation through said pipe line, a switch for controlling said pump and motor, and means contained within the chamber which discharges into the pipe line adapted to engage the switching mechanism for controlling the operation of the pump and motor, whereby the same is turned off or on as the water level in said discharging chamber reaches the predetermined low or high levels.

9. In a refrigerating apparatus, the combination of a refrigerating box, a storage tank partitioned off so as to form two chambers adapted to hold a cooling liquid, one of which is smaller than the other, means for siphoning the liquid from the large chamber to the smaller chamber, a pipe line connecting with the smaller chamber leading through the box and discharging into the larger chamber, means for forcing the cooling liquid from the smaller chamber into the pipe line and circulating the same therethrough, and a valve for controlling the flow of liquid from the large to the small chamber whereby the time required for discharging the cooling liquid from the smaller chamber may be increased or decreased thereby forcing a greater or smaller quantity of cooling liquid through the box.

10. In a refrigerator apparatus, the combination of a refrigerating box, two chambers, one a storage chamber for a cooling medium and the other a charge accumulating chamber, a bleeding conduit connecting the storage chamber with the charge accu-

mulating chamber, means for controlling the rate of bleeding, a conduit leading from the said charge accumulating chamber through the refrigerator box and returning the cooling medium to the storage chamber, a pump connected therewith for circulating the cooling medium therethru, and means associated with the charge accumulating chamber and governed by the cooling me-

dium level therein for controlling the operation of the pump, whereby the cooling medium is only at variable periods used for heat exchange in the conduit through the refrigerator box. 10

In testimony whereof I have affixed my ¹⁵ signature.
